UNITED STATES PATENT OFFICE.

HIRAM W. BLAISDELL, OF LOS ANGELES, CALIFORNIA.

STACKER.

No. 884,560.

Specification of Letters Patent.

Patented April 14, 1908.

Application filed June 22, 1906. Serial No. 322,868.

To all whom it may concern:

Be it known that I, HIRAM W. BLAISDELL, a citizen of the United States, residing at Los Angeles, in the county of Los Angeles, State 5 of California, have invented certain new and useful Improvements in Stackers; and I do hereby declare the following to be a full, clear, and exact description of the invention, such as will enable others skilled in the art to 10 which it appertains to make and use the same.

This invention relates to hydro-metallurgical apparatus and more particularly to mechanism designed for distributing or stacking the spent residue or tailings of hydro-metallurgical processes.

It is an object of this invention to provide an apparatus of this class that may be used upon a removable track and that will automatically run backward and forward on said 20 track throwing the material to either side.

It is also an object of this invention to provide an apparatus of this sort wherein the power used for progressing the apparatus 25 and for distributing the material, is derived independently of the conveyer which delivers the material to said apparatus.

Another object of the invention is to provide an apparatus of this character wherein 30 the distributing device may be operated to discharge the material in any desired direction.

A further object of the invention is to provide an apparatus that can be used to throw 35 the material in advance of itself until the pile of material is of sufficient height, whereupon tracks may be laid on top of it and the apparatus operated as at first described.

With these, and other objects in view, this 40 invention consists essentially in the construction and combination of parts herein described and illustrated in the accompanying drawings, in which

Figure 1 is a perspective view of the apparatus; Fig. 2 is a plan of the forward portion 45 of the same; Fig. 3 is a perspective detail of a portion of the reversing mechanism; Fig. 4 is an elevation of a portion of the rear of the apparatus, taken from the opposite side to Fig. 1; Fig. 5 is a diagrammatic view of the apparatus working upon a level surface; Fig. 50 6 represents the apparatus working upon an incline.

Reference numeral 1 designates an angle 55 bar or other suitable form of sill, whereon are

secured bearings 2 in which are journaled the axles 3 of supporting wheels 4. One end of each of said axles 3 has affixed thereto a worm gear 5. Said gears are inclosed in cases 6 and are engaged by worms 7, in the upper part of said case, said worms being on a shaft 8, on which are clutches 9 and 10.

Loosely mounted on shaft 8 are gears 11 and 12 in a case 13. A gear 14 on a cross shaft 15 meshes with gears 11 and 12. Cross shaft 15 has a worm gear 16, in case 17, driven by a worm 18 in the upper part of said case, said worm being connected by means of a flexible coupling 19 with the armature shaft of the motor 20, inclosed in housing 21, the front part of which 22, is removable to 60 65 70 allow access to the motor.

Clutches 9 and 10 have grooves 23, in which the forks 24 of shifter 25 (Fig. 3) rest. The upper end of shifter 25 is engaged by a 75 link 26, Fig. 1, the slotted end of which embraces a pin 27 upon a rocking lever 28, mounted on a shaft 29. The upper end of said rocking lever is supplied with a handle 30. The opposite end of shaft 29 carries 80 lever 31 and weight 32. The end of lever 31 has a stud 33, engaged by a lever 34, pivoted in a bearing on sills 1.

Angle bars 35 are supported vertically on sills 1, being braced by angles 36, on which are bearings 37, carrying a shaft 38, on which is pulley 39. At a point between angle 36 and the rear of the apparatus is an upright 40, supporting an angle 41, carrying a journal 42, which supports the shaft 43 of an 90 idler 44. Upon the sill 1 is a bearing 45, supporting a shaft 46 of an idler 47. The conveyer belt 48 travels over pulleys 39, 44 and 47, and is supported by troughing idlers 49 and bottom idlers, not shown. One end of 95 shaft 43 carries a sprocket 50, connected by a sprocket chain with a sprocket 51 upon the end of a shaft 52, journaled in bearings supported by upright 35. Shaft 52 has a gear 53, which drives the pinion 54, upon the end 100 of a shaft 55, said shaft being supported in bearings in the ends of arms 56. Shaft 55 carries a brush 57. Adjacent to pulley 39 is a hopper 58, the lower member of which 59, has a ring formed upon its upper edge, which 105 is held by cleats 60.

A centrifugal distributor 61 is supported immediately below member 59 on a turn-table 62, and is driven by means of a gear 63, driven by a pinion 64 on the armature shaft 110

of a motor 65, inclosed in housing 66. The forward end of turn-table 62 has a clamp 67, engaging a semi-circular angle plate 68, affixed to the front ends of sills 1. Troughing 5 idlers 69 are provided to guide the conveyer 48 as it goes onto the pulley 39. Trolleys 70 and 71 are provided to receive current from the trolley wires 72 and have suitable electrical connections with motors 20 and 65.

10 The ends of shafts 3, opposite to those carrying gears 5, have thereon spur gears 73, which mesh with a rack 74, laid parallel to the tracks 75 on which wheels 4 travel.

A stop 77 may be affixed to or near rails 15 75. A conveyer 76 may be provided to deliver material to conveyer 48, and a motor 78, at the head end of conveyer 48, may be provided to drive the same.

15 The mode of operation of this invention is 20 as follows: Material being deposited upon conveyer 76, is delivered thereby to conveyer 48 and carried up over pulley 39 and deposited in hopper 48 and deflected by the latter onto the distributer 61 and thrown in 25 the desired direction thereby. The conveyer 48, after leaving pulley 39, passes over and behind pulleys 44 and 47 and thence toward the front of the machine and to the pulley 78, driven by motor 77, from whence it 30 returns over the bottom idlers toward the conveyer 76. The motor 20, by means of the mechanism previously described, imparts motion to wheels 4, and the apparatus travels along the tracks 75 uniformly distributing material at the side thereof. When 35 the lever 34 contacts with one of the stops 76, motion is imparted to shaft 29, whereby the lever 28, the link 26, shifter 25 and clutches 9 and 10 are operated. By this 40 means the travel of the apparatus is reversed and it moves in the opposite direction until lever 34 contacts with the stop 77 at the opposite end of the tracks 75, whereupon the machine moves in the original direction.

45 When it is desired to throw the material to the opposite side of the machine, the motor 65 may be reversed, and the lower member 59 of the hopper 58 also revolved. When it 50 is desired to operate the machine upon an incline, the rack 74 is laid at the side of the track. The conveyer belt which may be the one designated by the numeral 77, is passed over the pulleys 39 and 44 and under the pulley 47, as shown in Fig. 6. The distributer 55 61 is turned to discharge the material toward the front of the apparatus. As the material accumulates in front of the machine, a new length of track is laid, the joining of the belt is opened and a new length inserted, motor 20 is started and the machine runs up the incline until the belt is again in tension. This operation may be repeated as often as may be desired.

Claims

65 1. In a traveling apparatus for discharging

material from a conveyer belt, means independent of said belt for propelling the apparatus and a distributer mounted on said apparatus.

2. An apparatus for discharging material 70 from a conveyer belt, means independent of said belt for propelling the apparatus and devices for reversing the direction of travel.

3. An apparatus for discharging material 75 from a conveyer belt, means independent of said belt for propelling the apparatus and devices for automatically reversing the direction of travel.

4. An apparatus for discharging material 80 from a conveyer belt and a motor on said apparatus for propelling the same.

5. An apparatus for discharging material 85 from a conveyer belt, an electric motor on said apparatus for propelling the same and means for supplying current to said motor. 85

6. An apparatus for discharging material 90 from conveyer belts, supporting wheels thereon, a motor mounted on said apparatus and power transmitting connections between said motor and wheels. 90

7. In an apparatus for discharging material 95 from a conveyer belt means consisting of idlers so arranged therewith, that the belt being rove thereover in one way, its lower lead may be caused to leave the apparatus moving in a direction contrary to the direction in which the upper lead is moving, or rove thereover in another way, said lower lead may be caused to leave the apparatus moving in the same direction in which said 100 upper lead is moving. 100

8. In an apparatus for distributing material, a discharge pulley, a first idler pulley, a second idler pulley and a conveyer belt passing over said discharge pulley, over said first idler pulley and under said second idler pulley leaving the apparatus in a reverse direction to that in which it approached said apparatus means for progressing said apparatus. 105

9. In a traveling apparatus for discharging material from a conveyer belt a rotary distributer mounted on said apparatus and automatic means for reversing the travel of said apparatus. 110

10. In an apparatus for discharging material from a conveyer belt, a traveling carriage, discharging and idler pulleys thereon and a rotary distributer to receive material from said conveyer belt and distribute the same and a motor to drive said distributer and automatic means for reversing the travel of said carriage. 115

11. In a traveling apparatus for discharging material from a conveyer belt, a distributer revolving on a horizontal axis carried by a support revoluble in a horizontal plane and automatic means to reverse the travel of said apparatus. 125

12. An apparatus for discharging mate- 130

- rial from conveyer belts, supporting wheels thereon, a motor mounted on said apparatus, power transmitting connection between said motor and wheels, a carriage and discharging 5 and idler pulleys mounted thereon.
13. In a traveling apparatus for discharging material from a conveyer belt a distributor and means for changing the direction of discharge of said distributor and a motor 10 mounted on said apparatus to drive said distributor and automatic means to reverse the travel of said apparatus.
14. In an apparatus for discharging material from a conveyer belt a motor mounted 15 upon said apparatus, connection between said motor and the supporting wheels of said apparatus and automatic devices in said connection for reversing the direction of rotation of said wheels.
15. In an apparatus for discharging material from conveyer belts, a motor mounted upon said apparatus, a worm connected to the armature shaft of said motor, a gear driven by said worm, a shaft driven by said 20 gear, a bevel gear on said shaft, bevel gears driven in reverse directions by said bevel gear, clutches connected with said driven gears, a shaft actuated by said clutches, worms on said shaft, and gears driven by 25 said worms on the axle of said apparatus.
16. In an apparatus for discharging material from conveyer belts a motor mounted upon said apparatus, connection between said motor and the supporting wheels of said 30 apparatus, devices in said connection for reversing the direction of rotation of said wheels, a lever connected with said devices and stationary contact pieces to operate said lever.
17. In an apparatus for discharging material from conveyer belts a motor mounted upon said apparatus, connection between said motor and the supporting wheels of said 35 apparatus, a gear upon the outer end of the
- axles of said supporting wheels and a stationary rack for said gear to mesh with. 45
18. In an apparatus for discharging material from conveyer belts, a motor mounted upon said apparatus, connection between said motor and the supporting wheels of said 50 apparatus, devices in said connection for reversing the direction of rotation of said wheels, a gear upon the outer end of the axles of said supporting wheels and a stationary rack for said gear to mesh with. 55
19. In a traveling apparatus for discharging material from conveyer belts, a rotary distributor and a pivoted support for said distributor and automatic means to reverse the travel of said apparatus. 60
20. In an apparatus for discharging material from conveyer belts, a rotary distributor, a motor to drive said distributor and a pivoted support for said motor and distributor. 65
21. In an apparatus for discharging material from conveyer belts, a rotary distributor, a motor to drive the same, a pivoted support for said distributor and motor and a hopper to deliver material to said distributor.
22. In an apparatus for discharging material from conveyer belts, a rotary distributor, a pivoted support for said distributor, a hopper to deliver material to said distributor and a revolute portion upon said hopper. 70
23. In an apparatus for discharging material from conveyer belts, a discharging pulley 39, a first idler pulley 44, a second idler pulley 47, a brush mounted adjacent to pulley 39, and means for operating said brush. 75
